UNITED STATES PATENT OFFICE.

HARRY B. HAUCK AND JOHN T. BARLOW, OF PHILADELPHIA, PENNSYLVANIA.

DESIGN FOR A FONT OF TYPE.

Application filed April 1, 1929. Serial No. 30,712. Term of patent 7 years.

To all whom it may concern:

Be it known that we, HARRY B. HAUCK and JOHN T. BARLOW, citizens of the United States, residing in Philadelphia, Philadelphia County, Pennsylvania, have invented a new, original, and ornamental Design for Font of Type, of which the following is a specification, reference being had to the accompany drawing, forming part thereof, the figure of which is a face view illustrating our new design for font of type.

We claim:—

The ornamental design for a font of type substantially as shown.

HARRY B. HAUCK.
JOHN T. BARLOW.
